J. WHITCOMB,
STARTING ATTACHMENT FOR ENGINES,
APPLICATION FILED APR. 2, 1918.

1,298,843.

Patented Apr. 1, 1919.

Inventor
James Whitcomb

By C. C. Hines,

Attorney

UNITED STATES PATENT OFFICE.

JAMES WHITCOMB, OF GOLDEN, COLORADO, ASSIGNOR OF ONE-FOURTH TO CHARLES ESPY BYERS, OF HASTINGS, NEBRASKA, ONE-HALF TO RALPH S. BUCHTEL, AND ONE-FOURTH TO BENJAMIN F. HEFFNER.

STARTING ATTACHMENT FOR ENGINES.

1,298,843.

Specification of Letters Patent.

Patented Apr. 1, 1919.

Application filed April 2, 1918. Serial No. 226,252.

To all whom it may concern:

Be it known that I, JAMES WHITCOMB, a citizen of the United States, residing at Golden, in the county of Jefferson and State of Colorado, have invented new and useful Improvements in Starting Attachments for Engines, of which the following is a specification.

This invention relates to starting attachments for internal combustion engines, the object in view being to facilitate the starting of engines particularly in cold weather or after the engine has been out of operation for a sufficient length of time to become cold.

A further object of the invention is to provide means for facilitating the starting of an internal combustion engine, which means is in the form of an attachment capable of being readily applied to the intake connection of an engine between the carbureter and the combustion chamber, at any desired point.

With these and other objects in view, the invention consists of the features of construction, combination and arrangement of parts, hereinafter fully described and claimed, reference being had to the accompanying drawing in which:

Figure 1 is a sectional view illustrating the improved device in its applied relation to an engine.

Fig. 2 is a detail perspective view of the device with the adjacent wall or plate removed.

Fig. 3 is a similar view of the inner plate or wall of the device and the parts carried thereby.

The device contemplated in this invention comprises a casing 1 which is generally cylindrical in formation and which comprises an outer wall 2, an inner wall 3 and a peripheral or circular wall 4, the latter being formed with a slot 5 to admit of the back and forth movements of the handle 6 of a cut off or shutter 7. The cut off 7 is pivotally mounted at 8 within the casing 1 and

is designed to cover and uncover a central opening 9 through the front wall 2 of the casing.

The inner wall or plate 3 of the casing is detachably connected to the peripheral wall 4 by any suitable fastening means and has projecting from its outer face a tubular nipple 10, the end portion of which is threaded as shown at 11 and screwed in the intake pipe or manifold of an engine between the carbureter and the combustion chamber.

Encircling the tubular nipple 10 is a cylinder housing or sleeve 12 the internal diameter of which is sufficiently greater than the exterior diameter of the nipple 10 to enable a body 13 of absorbent material, preferably asbestos, to be inserted around the nipple and within said sleeve, the asbestos projecting beyond one or both ends of the sleeve 12 so that a highly combustible hydrocarbon such as gasoline may be poured or squirted upon the material 13.

In the use of the device, it is preferred to employ a squirt can filled with gasoline or other highly volatile fuel oil and inject a small quantity of the same through the opening 9 into the casing 1. An additional amount of such fuel oil is squirted upon the absorbent material 13 and the gasoline or other oil is then ignited by a match. As the fuel is consumed the wall or plate 3 and nipple 10 are highly heated and the liquid fuel contained in the casing is correspondingly heated and generated into a highly explosive vapor. Then as the engine is turned over, such highly combustible gas is drawn into the engine by the suction of the latter thereby insuring a sufficient number of revolutions of the engine shaft to heat the engine to a point where it will take up its own cycle of operation with the carbureted air furnished directly by the carbureter.

The device hereinabove described is of the visible type, being located exteriorly of the engine where it is readily accessible and as above indicated it may be readily applied to any internal combustion engine.

Having thus fully described my invention, I claim:

A starting attachment for internal combustion engines, comprising a casing including disk-shaped inner and outer walls, the outer wall having an inlet opening therein for injection of a supply of liquid fuel, a cut off contained within said casing

between said walls and adapted to cover and uncover the inlet opening thereof, a tubular nipple projecting from said casing, absorbent material encircling said nipple, and retaining means for said absorbent material.

In testimony whereof I affix my signature.

JAMES WHITCOMB.
